RANGEFINDER-VIEWFINDER OR SIMILAR ARTICLE

James M. Conner, Glendale, Calif., and Bruce K. Johnson, Andover, Mass., assignors to Polaroid Corporation, Cambridge, Mass., a corporation of Delaware

Filed Oct. 23, 1965, Ser. No. 87,864

Term of patent 14 years

(Cl. D61—1)

FIG. 3 is a front view thereof;

FIG. 4 is a left side view thereof; and

FIG. 5 is a right side view thereof.

The fragmentary, broken-line showing of a camera is for illustrative purposes only.

We claim:

The ornamental design for a rangefinder-viewfinder or similar article, substantially as shown and described.
